His Attorney.

Patented Oct. 3, 1922.

UNITED STATES PATENT OFFICE.

BERNHARD TANG, OF SCHENECTADY, NEW YORK, ASSIGNOR TO GENERAL ELECTRIC COMPANY, A CORPORATION OF NEW YORK.

ELECTRIC FURNACE.

Application filed December 11, 1920. Serial No. 430,009.

To all whom it may concern:

Be it known that I, BERNHARD TANG, a citizen of the United States, residing at Schenectady, in the county of Schenectady, 5 State of New York, have invented certain new and useful Improvements in Electric Furnaces, of which the following is a specification.

The present invention relates to resistance 10 furnaces and comprises in particular a supporting structure for the heaters of electric resistance furnaces.

My invention is particularly applicable to the construction of large industrial furnaces, such as described for example in 15 Collins Patent, 1,310,060 of July 15, 1919. In furnaces of this type, heaters consisting of heavy bands or ribbons of refractory metal are hung upon supports projecting 20 away from the furnace wall.

It has been suggested to constitute these supports of fire brick having a butt portion which may be laid into the furnace wall and an outwardly projecting portion upon which 25 the resistor may be hung.

In accordance with my invention I have provided a furnace structure which is more durable and of greater electrical resistance at high temperatures by constituting the 30 heater support of a plurality of members; namely (1) one or more hangers for the heater, these hangers consisting of a high grade material, such as alundum (largely aluminium oxide Al_2O_3), which is strong me- 35 chanically and electrically non-conductive at the highest temperatures attainable in a resistance furnace and (2) a base for the hanger consisting of ordinary fire brick or similar low grade refractory material.

40 In the accompanying drawing, Fig. 1 is a perspective view partly in section of an embodiment of my invention, and Fig. 2 is a side elevation of a portion of the wall of an electric furnace embodying my invention.

45 Referring to the drawing, the hanger, as

shown in Fig. 1, comprises a shank 3 and a stem 5. The shank conveniently may be of cylindrical shape and provided with grooves 4. The stem 5 is provided with flanges 6, 7. The shank 3 is cemented, or otherwise 50 held, within a recess in a base member 8 consisting of fire brick or similar cheap refractory material.

As shown in Fig. 2, the base members 8 are laid into a furnace wall 9 and the resistors or heaters 10 are strung back and forth upon the stem 5 between the flanges 6, 7. The ends of the various resistor sections are connected by welding or brazing to terminals which pass through the wall. 60

What I claim as new and desire to secure by Letters Patent of the United States, is:—

1. An electric furnace heater support comprising a wall member consisting of refractory brick, and a hanger for an electric heater joined thereto, said hanger consisting of more highly refractory material than said brick. 65

2. A heater support for electric furnaces comprising two members, one which is adapted to be laid into a wall and the other being adapted to project from said wall to retain an electric heater in desired position, said outwardly projecting member consisting in part at least of alumina. 75

3. A heater support for electric furnaces comprising an anchoring member consisting of fire brick and a hanger cemented thereto consisting of alundum.

4. A heater support for electric furnaces comprising a brick consisting of refractory material and being provided with a recess and a hanger for an electric resistor having a shank adapted to be fitted within said recess and an outwardly projecting stem 85 having a plurality of flanges.

In witness whereof, I have hereunto set my hand this 10th day of December, 1920.

BERNHARD TANG.
